UNITED STATES PATENT OFFICE.

RICHARD HIRST, OF PHILADELPHIA, PENNSYLVANIA.

WOVEN PILE FABRIC.

1,064,482.

Specification of Letters Patent. Patented June 10, 1913.

Application filed October 28, 1912. Serial No. 723,095.

To all whom it may concern:

Be it known that I, RICHARD HIRST, a citizen of the United States, residing in Philadelphia, Pennsylvania, have invented 5 certain Improvements in Woven Pile Fabrics, of which the following is a specification.

My invention consists of a novel form of woven pile fabric intended mainly for carpets, rugs or upholstery purposes, and having on one face a cut pile and on the other face an uncut pile, either of which faces may be exposed as desired in the use of the fabric. 10

In the accompanying drawing Figure 1 represents an enlarged sectional view taken 15 in the direction of the warp and illustrating my improved fabric as it appears during the weaving, with a number of the pile wires still remaining in the pile loops and other pile loops being cut by the withdrawal of 20 the wires therefrom, and Fig. 2 represents an enlarged section of the fabric taken in the direction of the weft.

The fabric is composed of four sets of warp threads and two sets of weft threads. 25 The warp threads comprise the pile-forming warp 1, a stuffer warp 2 and two sets of binder warps 3 and 4, and the weft threads comprise an upper or top set 5 and a lower or back set 6. The stuffer warp 2 is introduced between the upper and lower sets of wefts 5 and 6, and the binder warps 3 and 4 are interwoven with the wefts of the upper set, the pile warp threads 1 being carried down between successive weft threads 5 and 30 35 looped around a corresponding lower weft thread 6, which is staggered in respect to the weft threads 5 of the upper set, as shown in Fig. 1.

In weaving the fabric, pile wires 7 are introduced in the usual way so as to cause the pile warp 1 to form loops on one face of the fabric, as shown at the left hand side of Fig. 1, which loops are cut by the withdrawal of the pile wires so as to produce the 40 45 cut pile tufts shown at the right hand side of Fig. 1, the looping of the pile threads around the lower wefts 6 forming, on the back of the fabric an uncut pile, whose loops are filled by the weft thread 6, these rows of 50 uncut pile being disposed so closely together as to be practically in contact with one another so as to provide an acceptable pile face on the back of the fabric free from all defects,

such as "grinning" of the stuffer or binder warp threads or the upper weft threads between the pile loops on the back of the fabric. But a single set of pile warp threads is employed, the colors of the pattern being printed upon these warp threads prior to the weaving of the same, so that each warp 55 60 thread presents a party-colored appearance as in weaving what are known as "tapestry" carpets, each color unit, however, being of greater length than it would be in a warp thread for a correspondingly patterned tapestry carpet woven in the ordinary way, because, in my improved fabric, the pile warp is carried to and around a weft thread on the back of the fabric and each color unit on each warp thread has to be long enough 65 70 75 to form the pattern in the uncut pile on the back of the fabric as well as in the cut pile on the face of the fabric, the patterns on both faces of my improved fabric being alike. 75

Fabric woven in accordance with my invention is very flexible but has no tendency to curl.

I claim:—

1. A woven pile fabric having a cut pile 80 on one face and an uncut pile on the opposite face both formed by the same pile warp threads, in combination with upper and lower like sets of weft threads, the pile forming warp threads passing between successive weft threads of the upper set and being looped around the corresponding weft threads of the lower set, whereby the rows of pile are disposed closely together on both faces of the fabric. 85 90

2. A woven pile fabric having a patterned cut pile on one face and a patterned uncut pile on the opposite face both formed by the same party-colored pile warp threads, in combination with upper and lower like sets 95 of weft threads, said pile forming warp threads passing between successive weft threads of the upper set and being looped around the corresponding weft threads of the lower set whereby the rows of pile are 100 disposed closely together on both faces of the fabric and a corresponding pattern is produced on each face of the fabric.

3. A woven pile fabric composed of upper and lower like sets of weft threads separated 105 by longitudinal stuffer threads, pairs of

1,084,489

binder warp threads interwoven with the
weft threads of the upper set and pile-forming
warp threads passing between successive
weft threads of the upper set and looped
around the corresponding weft threads of
the lower set.

In testimony whereof, I have signed my

name to this specification, in the presence of
two subscribing witnesses.

RICHARD HIRST.
